CLAIM

The ornamental design for a clip for bundled articles, as shown and described.

DESCRIPTION

FIG. 1 is a front perspective view of a clip for bundled articles showing our new design;

FIG. 2 is a rear perspective view thereof;

FIG. 3 is a front elevation thereof;

FIG. 4 is a rear elevation thereof; and

FIG. 5 is a right side elevation thereof, wherein a left side elevation is a mirror image of the right side elevation; and, FIG. 6 is a top plan view therefore, wherein a bottom plan view is the same as the top plan view.

In the drawings, the broken lines depict unclaimed subject matter only and form no part of the claimed design.
